THIRTY-SIX SPEED HEAD

Filed March 28, 1925

UNITED STATES PATENT OFFICE

DAVID C. KLAUSMEYER AND HENRY M. NORRIS, OF CINCINNATI, OHIO, ASSIGNEES TO
THE CINCINNATI BICKFORD TOOL COMPANY, OF CINCINNATI, OHIO, A CORPORA-
TION OF OHIO

THIRTY-SIX-SPEED HEAD

Application filed March 28, 1925. Serial No. 19,178.

This invention relates to radial drilling and tapping machines and it deals more particularly with means to rotate the tool spindle journaled in the tool-head, adjustably supported on the radial arm. These spindles are adapted to carry various types and sizes of tools, such as drills and taps of varying diameters, and inasmuch as each of these tools requires a different speed of rotation for maximum efficiency it is essential that means be provided for regulating the speed of rotation of the spindle.

Heretofore this has usually been accomplished by providing, adjacent the prime mover, and remote from the drill-head, a speed-change mechanism, (hereinafter called the speed-box) adapted to provide a plurality of speeds, usually six, which were transmitted to a shaft journaled lengthwise of the radial arm. These six speeds were usually multiplied by four by another speed-change mechanism, commonly known as the "back gears," which were located in the tool-head and operatively connected with the tool-spindle. Thus by manipulation of both of the speed-change mechanisms any one of twenty-four speeds selectively could be secured in the tool-spindle from a single speed in the prime mover. The differences in ratio afforded by the speed box are necessarily small since there is considerable mechanism actuated thereby and great differences in ratio would effect abrupt changes and cause strains that would be detrimental to the parts. Inasmuch as only the spindle is actuated by the back-gears the speed-changes provided therein may be materially greater than those provided by the speed-box.

To effect a predetermined speed in the spindle it has heretofore been necessary for the operator first, by the manipulation of certain control levers carried by the tool-head, to shift the back-gears and thereby obtain the nearest approximate speed obtainable therein, and second, to leave his position at his work and go to the opposite end of the machine where, by manipulation of the speed-box control-lever, he effected the finer and more accurate speed setting. This remote location of the finer speed changes ren-

ders their frequent adjustment inconvenient and bothersome and therefore the tendency of the operator is to ignore the finer speed settings and to rely on the nearest speed obtainable in the back-gears, which he may shift from his position at his work. This employment of improper spindle speeds necessarily results in loss of efficiency and is likely to prove detrimental to the tool should too great a speed be employed.

This invention has for an object to provide improved means, located wholly within the drill-head, for selectively rotating the tool-spindle at any one of a greater number of speeds than has heretofore been provided by both the speed-box and the back-gears.

More specifically stated, this invention has for an object to provide, within the tool-head, three independent serially arranged speed-change mechanisms each adapted to multiply the speeds produced by the preceding speed change mechanism, or mechanisms, by means of which any one of thirty-six speeds selectively may be produced in the tool-spindle from a single speed in the arm shaft.

Another object of this invention is to provide an improved driving connection between the spindle and its driving sleeve and between the sleeve and its actuating gear unit whereby a balanced drive in the spindle is secured, twist in the spindle is eliminated and the parts may be more freely translated, when under heavy pressure, than in prior constructions.

These objects have been attained by embodying in a radial drill head three speed-change mechanisms namely primary, secondary and tertiary change gear-sets affording respectively three, three and four speed changes, which, multiplied together, render available thirty-six speeds in the spindle from a single speed in the arm shaft. These gear-sets are so constructed and arranged that only four gear or clutch units are required to be shifted to produce all of the thirty-six speeds and these units are adapted to be shifted by suitable levers carried by the tool-head where they are all readily accessible to the operator when stationed at his work.

The tool-spindle is translatable carried by a spindle-driving sleeve rotatably journaled in the drill-head and a clutch member splined to the sleeve serves to transmit rotation to the sleeve and spindle at any one of the thirty-six available speeds. To effect a balanced drive of the spindle the spindle and sleeve are preferably connected together by means of four equally spaced ways cut in the 5 spindle, which are engaged by splines formed on the inner surface of the sleeve. This provision and location of the four driving connections between the sleeve and spindle gives a greater spline area and so evenly 10 distributes the power applied to the spindle that the spindle is maintained freely translatable in the sleeve even when great power is being transmitted. Also the four splines engage the ways in the spindle only adjacent 15 to the lowermost bearing for the sleeve thereby applying the power to the spindle at a point nearer to the tool than heretofore and eliminating a certain amount of distortion in the spindle which also has prevented free 20 translation of the spindle.

The outer surface of the spindle driving sleeve also is formed with four equally spaced splines by means of which the final power transmitting clutch-element is slidably secured to the sleeve.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:—

Fig. 1 is a sectional development showing 45 the improved speed-regulating mechanism connecting the horizontal arm shaft of a radial drill with the tool spindle (all of this mechanism being embodied in the tool-head).

Fig. 2 is a section on the line 2—2 of Fig. 1. 50 Fig. 3 is a section on the line 3—3 of Fig. 1.

Fig. 4 is a diagrammatic view illustrating the flow of power through the three serially arranged speed-change mechanisms.

Referring to Fig. 4 the scheme of the present improved spindle rotating mechanism will be understood. Power is introduced into the tool-head by means of a single speed shaft P, (which in practice preferably is the horizontal shaft journaled lengthwise of the radial arm). This shaft is connected, as by 55 means of bevel gears indicated at X to a driven shaft 1. A primary speed change mechanism A comprising gears a, b, c, d, f and g and a clutch element e may selectively be engaged as indicated in Fig. 4, to transmit to a shaft 2 any

one of three speeds from a single speed in the shaft 1. A second speed change mechanism B comprising gears c, h, i, j, k, l, and clutch elements j' and l' triple the three speeds transmitted thereto and produce nine speeds 70 in a shaft 3. A third speed change mechanism C connects the shaft 3 with a spindle rotating sleeve 5 and multiplies by four the nine speeds of the shaft 3 into thirty-six speeds in the sleeve 5 and the spindle S driven thereby. 75 The four trains of mechanism for multiplying the nine speeds delivered to the mechanism C comprise 1st:—gears m, n, o, p, shaft 4, gears q, r and clutch elements s and t. 2nd:—gears m, n, and o and clutch element v. 80 3rd:—clutch elements w, x, gears p, o, and clutch elements v. 4th:—clutch element w, x, shaft 4, gears q, r and clutch elements s and t. Thus it will be seen that by means of three independent serially arranged speed 85 change mechanisms A, B and C, all of which are carried by the tool-head, the single speed in the shafts P and 1 is multiplied into thirty-six speeds in the spindle S.

Referring now more particularly to Fig. 90 1 the mechanism for selectively securing any one of the thirty-six speeds will be more clearly understood. The power shaft P carries two bevel gears (of which only one (6) is shown) which mesh with diametrically opposite sides of a similar gear 7 fixed upon a vertical shaft 1 journaled in bearings 8 and 9 supported by the tool-head. Splined to the shaft 1 is a gear unit 10, adapted to be shifted axially of the shaft 1 by a suitable gear shifting lever (not shown) carried by the tool-head. This gear unit provides gears a and b adapted selectively to be meshed with gears c and d keyed to a shaft 2, also journaled in the tool-head, as by bearings 11 and 12. A gear-unit 13 is rotatably journaled on a bushing 14 coaxial with the shaft 1. The gear unit 13 provides a clutch element e, adapted to be engaged by the gear b, and a gear f, permanently in mesh with a gear g, fixed upon the shaft 2. 110 The gears a, b, c, d, f and g and the clutch element e, constitute the primary speed change mechanism A hereinbefore referred to (see Fig. 4) which delivers three speeds to the shaft 2 from a single speed in the shaft 1.

The second speed-change mechanism B, which triples the speeds in the shaft 2, comprises gears h, i and k fixed to the shaft 2, which are adapted to drive gears j, l and l', respectively, carried by a shaft 3 journaled in bearings 15 and 16 carried by the tool-head. The gears i and j constitute a gear-unit 17 splined to the shaft 3 and adapted to be shifted thereon by a suitable lever carried by the tool-head. The gear l is loosely journaled on a bushing 18, coaxial with the shaft 3, and is formed with a clutch element l' adapted, in a certain position of the gear unit 17, to engage a similar clutch-element j' on said gear-unit, thereby to establish a driv- 125 130 135

ing connection between the gear *l* and the shaft *3*.

The nine speeds in the shaft *3* are multiplied by four by the third speed-change mechanism *C*, usually known as the back-gears, now to be described. Upon the shaft *3* is splined a shiftable gear-unit *19* formed with a gear *m* and a clutch element *w*. The clutch-element is adapted to be brought into driving engagement with a clutch-element *x* formed in a member *20* fixed upon a shaft *4* journaled in the tool-head with its axis in line with the axis of the shaft *3*. The shaft *4* carries a gear *q* which is adapted to transmit slow rotary motion to the sleeve *5* and spindle *S* through its connection with a large gear *r*, provided by a gear-member *21*, loosely journaled coaxial with said sleeve and adapted to be secured thereto by means of a clutch element *s*. This clutch element designed to be engaged by a clutch element *t* provided by a clutch member *22* splined to the sleeve *5*. The sleeve *5* is journaled in bearings *25* and *26* carried by the tool-head, a portion of which is indicated at *27*, nuts threaded upon opposite ends of the sleeve engage the bearings *25* and *26* and prevent end-wise movement of the sleeve in the tool-head. Slow motion may also be transmitted from the gear-unit *19* by meshing the gear *m* therewith of a gear *n* forming a part of a gear unit *23* loosely journaled on a bushing *24* surrounding the spindle. The gear unit *23* also provides a gear *o* permanently in mesh with a gear *p*, provided by the member *20*. With the gears *m* and *n* in mesh power flows from the gear-unit *23* through gears *o* and *p* to the member *20* and thence through shaft *4*, gears *q* and *r* and clutches *s* and *t* to the spindle driving sleeve *5*. The clutch member *22* also provides a clutch element *v* adapted, in the lowermost position of the member, to engage the gear *o* and thus receive motion from the gear-unit *19*, either through clutch members *w* and *x*, and gears *p* and *o*, or gears *m*, *n* and *o*.

As hereinbefore stated this invention provides improved means for so rotating the spindle driving sleeve and the spindle translatable mounted therein that a balanced drive is effected and the parts may be more easily shifted, when transmitting great power, than in prior constructions. To that end the sleeve *5* is formed on its outer surface intermediate its ends, with four equally spaced splines *28*, adapted to fit within ways *29* formed in the inner periphery of the clutch member *22*. The sleeve *5* is also formed on its inner surface, adjacent its lower end, with four equally spaced splines *30* fitted within spline ways *31* formed in the spindle *S*. It is to be noted that the sleeve *5* is of substantial size and well adapted to withstand the torsional strains to which it is subjected. Also that the splines *30* engage the spindle *5* within

the bearing *25* and at the nearest possible point to the tool-carrying end of the spindle. By means of this construction the power to rotate the sleeve and spindle is divided and applied equally to four sides of the sleeve and spindle, thus producing a balanced drive and reducing the friction between the splines and their cooperating ways. Furthermore this construction precludes twisting of the spindle during the drilling operation thereby the spline ways are maintained in perfect alignment with the splines and the parts are free to be translated to effect the feed of the tool into the work.

From the foregoing it will be perceived that there has been provided a new and improved power transmission, wholly embodied within the tool-head, whereby a greater variety of spindle speeds is rendered available, and by means of which the operator may employ any available speed without leaving his position at his work.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention, and, therefore, such adaptations should be, and are intended to be, comprehended within the meaning and range of equivalency of the following claims.

Having thus revealed this invention, we claim as new and desire to secure the following combinations and elements, or equivalents thereof, by Letters Patent of the United States:

1. In a radial drill head, a speed controlling mechanism combining a power shaft; first, second, and third driven shafts; a spindle; serially arranged primary, secondary and tertiary gear sets carried by the head and adapted to transmit to said spindle a plurality of speeds from a single speed in said power shaft, said secondary gear set comprising three rotatable and non-translatable driving gears supported by said second shaft, one rotatable and non-translatable driven gear journaled coaxial with said third shaft and two driven gears splined to said third shaft, said driven gears being complementary to said driving gears, and being adapted selectively to be rotated thereby; and a clutch device between said translatable and non-translatable driven gears operatively to connect said non-translatable driven gear with said third shaft.

2. In a radial drill, a speed controlling mechanism combining a power shaft; first, second and third driven shafts 1, 2 and 3 respectively; a spindle; serially arranged primary, secondary and tertiary gear sets carried by said head and adapted to transmit to

said spindle a plurality of speeds from a single speed in the power shaft; said primary and secondary gear sets comprising a driving gear rotatably and non-translatably journalized on the first shaft 1, a gear unit comprising two gears splined to said first shaft 1; a clutch device between the non-translatable gear and said gear unit; five gears non-translatably mounted on said second shaft 2, three of said five gears being complementary to the three gears on the first shaft 1; a two gear unit splined to the third shaft 3; one gear rotatably journalized on said third shaft 3 and maintained permanently in mesh with one of the gears on the second shaft 2; a clutch device between the last named gear and the two gear unit, the two gears of said unit being selectively engageable with two of the gears on the second shaft 2, one of the gears on the second shaft 2 serving both as a driven gear for the first gear set and as a driving gear for the second gear set.

3. A speed controlling mechanism for drill heads combining a power shaft; a first speed change mechanism comprising a second shaft 1 adapted to be driven from said power shaft; a gear-unit 10 splined to said second shaft and providing two gears *a*, *b*, of which one is also adapted to serve as a clutch element; a member 13 rotatably journalized co-axial with one of said shafts and providing a gear *f* and a clutch element *e*, the latter being adapted to be engaged by said combined gear and clutch element; a third shaft 2, three gears *g*, *d*, *c* splined to said third shaft of which one meshes with the gear on said member 13; means permitting the shifting of the gear-unit 10 selectively to mesh the gear *b* with the clutch element *e* and the gear *d*, and the gear *a* with the gear *c* to transmit three speeds to the shaft 2; a shaft 3; a second speed change gear mechanism connecting the shafts 2 and 3 for tripling the three speeds produced in the first speed change mechanism; and a set of back-gears to multiply the nine speeds produced in the first and second speed change mechanisms.

4. In a machine tool, in combination; a spindle; a power shaft; first, second and third driven shafts, 1, 2 and 3, arranged substantially in parallelism, the first being driven from the power shaft; a two-gear unit splined to the first shaft 1; a single gear rotatably journalized co-axial with the first shaft 1; three driven gears *c*, *d* and *g* fixed to the second shaft 2, one of said three gears being permanently in mesh with said single gear; means permitting the gears of the two-gear unit selectively to be meshed with two of the gears fixed to the second shaft 2 and means to clutch the single gear to the first shaft 1 selectively to give to the second shaft 2 rotation at increased or reduced rates from the first shaft 1; a drive gear secured to the sec-

ond shaft 2; a gear *l* rotatably journalized co-axial with the third shaft 3 and permanently in mesh with the drive gear on the second shaft 2; a second drive gear secured to the second shaft 2; a gear unit splined to the third shaft 3 and affording a gear adapted to mesh with the second drive gear on the second shaft 2 and a gear adapted to mesh with one of the driven gears on the second shaft 2; means to clutch the rotatably journalized gear *l* to the third shaft 3; and back-gear mechanism connecting the third shaft 3 with the spindle to multiply in the spindle the number of speeds transmitted to said third shaft 3.

5. In a machine tool, in combination; a power shaft; a spindle; first and second serially arranged speed change mechanisms receiving rotation from the power shaft and each providing speed increasing and speed reducing gearing, for varying the speed received from said power shaft; said speed change mechanisms comprising first, second and third shafts, two gears splined to the first shaft, a gear journalized co-axial with said first shaft, means to clutch the last named gear to the first shaft; five gears fixed to the second shaft two of which selectively may be meshed with two of the gears on the first drive shaft and one of which is permanently in mesh with the gear journalized co-axial with said first shaft, two gears splined to the third shaft and adapted selectively to be meshed with two of the gears on the second shaft, a single gear rotatably journalized co-axial with the third shaft and permanently meshing with one of the gears fixed to the second shaft, means to clutch the last named gear to the third shaft, and a speed increasing and reducing back-gear mechanism, connecting the third driven shaft with the spindle and adapted to multiply by four the speeds provided by the first and second speed change mechanisms.

In witness whereof we have hereunto subscribed our names.

HENRY M. NORRIS.
DAVID C. KLAUSMEYER.
